Primary Examiner — Karen E Kearney*Assistant Examiner* — Nathaniel D Buckner(74) *Attorney, Agent, or Firm* — Dale F. Regelman; Quarles & Brady LLP(57) **CLAIM**

The ornamental design for a modified drum transponder, as shown and described.

DESCRIPTION

FIG. 1 is a perspective view of the design of this invention; FIG. 2 is a second perspective view;

FIG. 3 is a front side view;

FIG. 4 is a rear side view;

FIG. 5 is a first side view;

FIG. 6 is a second side view;

FIG. 7 is a top view; and,

FIG. 8 is a bottom view.

In the drawings, the broken lines showing an electrical cable illustrate environment and form no part of the claimed design.
